CIGARETTE-WRAPPING DEVICE

George L. Rogers, Inglewood, Calif., assignor to
Ione Barian Rogers, Inglewood, Calif.

Application September 25, 1942, Serial No. 459,720

2 Claims. (Cl. 131—52)

This invention relates to devices for making cigarettes and more particularly to devices of this type intended for hand operation.

Devices of this character are well known in the art and as they are used primarily by amateurs for rolling their cigarettes at home it is important that they be as simple in operation as possible and require the minimum of judgement on the part of the operator.

The object of the present invention is to provide a device of the character indicated embodying a simple attachment by means of which the cigarette wrap can be accurately positioned so as to assure a correctly rolled cigarette without interfering with the rolling operation.

A further object is to provide a paper-holding attachment which can be readily applied to devices of the general character indicated already known and on the market without any substantial modification of the original devices.

Various other objects of the invention will more particularly appear in the course of the following detailed description.

The invention consists in the novel construction, arrangement and combinations of parts hereinafter more particularly described and claimed.

One sheet of drawings accompanies this specification as part thereof in which like reference characters indicate like parts throughout.

In the drawing:

Figure 1 is a side elevation of an improved cigarette-rolling device embodying the present invention;

Figure 2 is a vertical transverse cross section taken on line 2—2 of Figure 1; and

Figure 3 is a perspective view of the wrap holder attachment removed from the cigarette-rolling device.

The present invention is herein illustrated as comprising a base 1 upon which are mounted spaced parallel longitudinally extending flanges 2 between which is mounted a platform 12 of inverted U-shape.

Pivoted between the flanges 2—2 as by rivets 5 are the spaced parallel arms 3—3 of a roller-carrying frame which is adapted to embrace and be rocked over the platform 12. The arms 3—3 are connected at their outer ends by a transverse member 4, serving as a handle and each of the arms 3 is formed with a medial enlargement 6, the function of which will hereinafter appear. Between the arms 3—3 is rotatably mounted a roller 7 adjacent the outer

portion of the enlargement 6, the roller 7 being of a length substantially equal to the width of the platform 12.

5 A flexible apron 8 of the same width as the platform 12 is provided having its end edges formed as a hem (not shown) and the apron 8 is of sufficient length to extend over the platform 12 and have its ends secured to the platform 1 adjacent the ends thereof as by wires 9 passing through the end hems of the apron and also through holes in the side flanges 2—2, each of the wires 9 having one end formed with a loop portion 10 adapted to rockingly engage the end of flange 2 to secure the wire 9 in position with respect to these flanges. The apron 8 is of sufficient length so that when secured by its ends to the platform 1 and extending over platform 12 and roller 7 there will be sufficient slack to form a loop between the platform 12 and the roller 7 as illustrated in Figure 1, this loop P constituting a pocket, the ends of which are closed by the enlargements 6—6 on the arms 3—3, which pocket is adapted to receive the tobacco which is to be rolled into a cigarette.

10 15 20 25 30 35 40 45 50 55 With the device as thus described after a cigarette wrapper is properly positioned over the apron 8 on the top of platform 12 and the arms 3—3 are rocked to the right the advance of roller 7 over the platform 12 operates to produce a rolling effect on the tobacco in the pocket P gradually compressing this tobacco in cylindrical form as it approaches the top of the platform where the cigarette wrap is positioned, at which point the tobacco engages the wrap and is rolled with it into the form of a cigarette which is discharged as a completed article at the right hand side of the device.

The construction thus far described is known and illustrated in my co-pending application Serial No. 397,614, filed June 11, 1941, now Patent No. 2,298,086, of which application the present application is a continuation in part.

In connection with such a device the proper 45 positioning of the cigarette wrap W with respect to the platform 12 while quite essential to the successful production of a cigarette is a matter of chance or judgment on the part of the operator unless some means is provided to accurately and 50 properly position this wrap. The provision of such a guide for the wrap to properly hold the paper with respect to the platform 12 must not interfere with the rocking of the arms 3—3 and roller 7 over the platform 12 and to accomplish 55 this object I provide a paper-holding attach-

ment which consists essentially of a frame which may be formed of wire bent to provide parallel spaced arms 15—15 connected by a portion 26 substantially perpendicular thereto upon which is secured a platform 25 by having one edge of the platform 25 bent around the connecting portion of the wire 26 to provide a rotatably adjustable connection by frictional engagement with the wire. The opposite edge of the platform 25 is turned upwardly as at 27 to provide a gauge abutment against which the edge of the cigarette wrap W can contact and thus assure its proper positioning transversely of the platform 12. The free ends 17—17 of the arms 15—15 are inturned in axial alignment to constitute pivots which are adapted to seat in suitable holes 18 which may be drilled in the sides of the base 1. A spiral spring 20 is associated with one of the arms 15 at its inturned pivot end 17 and arranged to resiliently bias the frame and platform 25 carried thereby to a predetermined position over the platform 12 where the arms 15 will engage and be stopped by the outturned lugs 28—28 struck from the flanges 2—2.

In operation the process of making a cigarette is substantially the same as that previously described, but it will be noted that as the arms 3—3 approach a vertical position the enlargements 6 will contact the ends of the connecting portion 26 as the forward edge of the cigarette wrap W is engaged by the advancing roll of tobacco and that the further advancement of the roller 7 over the platform 12 will carry the platform 25 with its supporting frame with it so that the paper support and gauge are rocked in advance of the cigarette-rolling device without any interference with the rolling operation. Upon the completion of the rolling of a cigarette the return of the roller 7 to the left releases the paper support and its frame which is automatically 40 returned to its initial position by the spring 20.

Various modification in the precise construction and arrangement of the parts will readily suggest themselves to those skilled in the art, but within the scope of the present invention as 5 claimed.

What I claim is:

1. In cigarette making apparatus having a platform, an apron positioned over the platform and a roller positioned intermediate the platform and apron, said roller mounted on a frame pivoted with respect to the platform, means for positioning a cigarette paper with respect to the platform comprising a frame pivotally mounted with respect to the platform, means for resiliently biasing said latter frame to a predetermined position over the platform, a table member for supporting papers mounted on said last mentioned frame, said table including a gauge member adapted to correctly align the paper thereon, the roller carrying frame being arranged to engage and retract the paper support frame as specified.
2. In cigarette making apparatus including a base, a platform, an apron extending over the platform and a roller adapted to pass between the platform and apron, a frame member formed with a part substantially parallel with and transversely disposed over the platform and apron, a paper supporting table member adjustably 30 mounted by one edge on said transverse part and having its other edge formed with a flange to constitute a paper gauge, said transverse part having depending end legs, the lower ends of which are inturned to form pivotal supports in the base, spring means interposed between the base and one of the depending end legs, and a pivotal frame for the roller, said roller frame arranged to engage and rock the frame for the table member.

GEORGE L. ROGERS.
